United States Patent Office

Des. 183,886
Patented Nov. 11, 1958

183,886

RADIO OR TELEVISION STAND

Roland N. Iverson, Dallas, Tex., assignor to Rolee Hospital Television, Inc., Dallas, Tex., a corporation of Texas

Application July 24, 1957, Serial No. 47,069

Term of patent 14 years

(Cl. D33—14)

The figure is a perspective view of a radio or television stand, showing my new design.

I claim:

The ornamental design for a radio or television stand, as shown.

References Cited in the file of this patent

UNITED STATES PATENTS

D. 157,868 Horn ----- Mar. 28, 1950

D. 160,663 Ruch ----- Oct. 24, 1950
2,596,749 Webber ----- May 13, 1952

OTHER REFERENCES

Interiors, June 1955, page 91, bottom right of page, bedside table.

Gift and Art Buyer, July 1951, page 84, right side of page, second from bottom, cup and saucer holders.